TAPE DISPENSER

Raymond P. Stoy, White Plains, N.Y., assignor to Nashua Corporation, Nashua, N.H., a corporation of Delaware

Filed Sept. 29, 1964, Ser. No. 81,927

Term of patent 14 years

(Cl. D74—1)

FIG. 1

FIG. 2

FIG. 3

FIGURE 1 is a side elevational view of the tape dispenser.

FIGURE 2 is a front perspective view.

FIGURE 3 is a front elevational view of the dispenser.

The undisclosed side of the dispenser is substantially the same, but for the absence of the handle lever, as the side shown and the undisclosed back consists essentially of a pair of plane surfaces completing the symmetrical body of the dispenser as shown in the drawing.

I claim:

The ornamental design for a tape dispenser, substantially as shown and described.
